AIR COOLING INTERNAL COMBUSTION ENGINE

Filed Nov. 11, 1922

FIG. 1.

FIG. 2.

INVENTOR.

Sam D Heron
BY

Robert H Young ATTORNEYS.

UNITED STATES PATENT OFFICE.

SAM D. HERON, OF DAYTON, OHIO.

AIR-COOLING INTERNAL-COMBUSTION ENGINE.

Application filed November 11, 1922. Serial No. 600,309.

This invention pertains to the cooling of internal combustion engines and more specifically to means for directing a cooling fluid over an internal combustion engine of the single-row-in-a-line type for airplanes or mechanical transport vehicles.

It is an object of the invention to simplify the cooling of engines of the type referred to and to insure the efficient working of such means.

It is a further object of the invention to sensibly and uniformly distribute the air supply to all the cylinders.

It is a further object to provide an arrangement whereby the engine housing will be substantially divided along a medial line to facilitate and direct the cooling of the engine and whereby the hood of the engine may be lifted or removed from either side as is usual with automobile engines of the present day providing a clear view of the engine without the necessity of removing further obstructions.

Other objects will appear infra, as the description of a specific embodiment of the invention proceeds and as claimed.

In the drawing:

Fig. I is a side elevation of an engine and hood partly in section, showing the invention; and

Fig. II is a top plan view of the engine and hood with parts cut away to show the application of the invention thereto.

The invention is designed for cooling internal combustion engines efficiently by air and for this purpose there is provided a baffle partition 2 shaped as shown in Fig. I to divide the engine space in two. To one end of this baffle 2 is connected a deflecting plate or baffle 4 whereby air drawn in to the engine space through a dummy radiator or other opening 6 by fan 8, is forced to pass down on one side of the cylinders 10 of the engine and forced out on the other side. In order to prevent the momentum of the air

drawn in carrying it (the air) past the first cylinders, a curved deflecting plate 12 is attached to one side of the engine hood 14. This plate 12 forces the air between the fins of the front cylinders of the motor, thus insuring equal distribution of the cooling medium.

The structure is so designed that air will be forced across the engine in the manner noted from Fig. I that I provide hinges 16 shown in the arrows in Fig. II. It will be for the usual hood covers and the covers and hinge mechanism may be designed to be removed, as is now common in the art, either together or alone with the baffle mechanism 2 etc., as desired, but I do not limit myself to any specific manner of removal operation.

What I claim is:

1. In a cooling system for internal combustion engines having a plurality of cylinders, a hood surrounding said engine, means at the forward end of said hood for inducing a flow of cooling medium into said hood, baffle means on one side of said hood adapted to guide said cooling medium to the opposite side of said hood, and a substantially arcuate shaped baffle plate positioned laterally of said second named side of said hood for guiding the flow of cooling medium tangentially past said cylinders.

2. In a cooling system for internal combustion engines having a plurality of cylinders, a hood surrounding said engine, means at the forward end of said hood for inducing a flow of cooling medium into said hood, baffle means on one side of said hood adapted to guide said cooling medium to the opposite side of said hood, and a second baffle means positioned laterally of said second named side of said hood for guiding the flow of cooling medium tangentially past said cylinders.

In testimony whereof I affix my signature.

SAM D. HERON.
